DESCRIPTION

FIG. 1 is a first perspective view of an ultrasonic diagnostic system;
FIG. 2 is a second perspective view of the ultrasonic diagnostic system;
FIG. 3 is a front view of the ultrasonic diagnostic system;
FIG. 4 is a rear view of the ultrasonic diagnostic system;
FIG. 5 is a left side view of the ultrasonic diagnostic system;
FIG. 6 is a right side view of the ultrasonic diagnostic system;
FIG. 7 is a top view of the ultrasonic diagnostic system;
FIG. 8 is a bottom view of the ultrasonic diagnostic system;
FIG. 9 is an enlarged view of part 9 as shown in FIG. 8;
FIG. 10 is an enlarged view of part 10 as shown in FIG. 2;
FIG. 11 is an enlarged view of part 11 as shown in FIG. 2;
FIG. 12 is an enlarged view of part 12 as shown in FIG. 2;
FIG. 13 is an enlarged view of part 13 as shown in FIG. 2;
FIG. 14 is an enlarged view of part 14 as shown in FIG. 2;
FIG. 15 is an enlarged view of part 15 as shown in FIG. 2;
FIG. 16 is an enlarged view of part 16 as shown in FIG. 2;
FIG. 17 is an enlarged view of part 17 as shown in FIG. 2;
FIG. 18 is an enlarged view of part 18 as shown in FIG. 3;
FIG. 19 is an enlarged view of part 19 as shown in FIG. 3;
FIG. 20 is an enlarged view of part 20 as shown in FIG. 3;
FIG. 21 is an enlarged view of part 21 as shown in FIG. 3;
FIG. 22 is an enlarged view of part 22 as shown in FIG. 4;
FIG. 23 is an enlarged view of part 23 as shown in FIG. 4;
FIG. 24 is an enlarged view of part 24 as shown in FIG. 4;
FIG. 25 is an enlarged view of part 25 as shown in FIG. 4;
FIG. 26 is an enlarged view of part 26 as shown in FIG. 8;
FIG. 27 is an enlarged view of part 27 as shown in FIG. 8;
FIG. 28 is an enlarged view of part 28 as shown in FIG. 8;
FIG. 29 is an enlarged view of part 29 as shown in FIG. 8;
and,
FIG. 30 is an enlarged view of part 30 as shown in FIG. 8.
The broken lines in the drawings depict portions of the
ultrasonic diagnostic system that form no part of the claimed
design.
